UNITED STATES PATENT OFFICE.

LOUIS CHASAN, OF NEW YORK, N. Y., ASSIGNOR TO SHUR LOC ELEVATOR SAFETY COMPANY, INC., OF NEW YORK, N. Y., A CORPORATION OF NEW YORK.

ELEVATOR.

Application filed August 21, 1923. Serial No. 658,480.

To all whom it may concern:

Be it known that I, LOUIS CHASAN, a citizen of the United States, residing in the borough of Bronx, in the city of New York and State of New York, have invented certain new and useful Improvements in Elevators, of which the following is a specification, reference being had to the accompanying drawings, forming a part hereof.

10 This invention is concerned particularly with the means whereby the elevator car gate or the shaft door or both, are operated by power under the control of the operator, and to the interlocking devices by which the 15 movement of the car is prevented when the car gate or the shaft door is unlocked for movement. In the embodiment of the invention which is illustrated and described herein, there is mounted on the car a carriage 20 which is reciprocated by power under the control of the operator, such carriage being directly connected with the car gate by means which permit the ready disconnection of the two when necessity arises, and provision is made by improved means for effecting operative connection between the carriage and each shaft door, under the control of the operator when the car is in position for such operation, the means being of such a 25 character that there is no liability to breakage during the movement of the car by reason of carelessness on the part of the operator or accident. Provision is also made whereby the car switch, by which the movement of 30 the car is controlled, is locked mechanically before the opening movement of the gate or door is commenced and is kept locked throughout the opening and the closing movement of the gate or door until the gate or door is returned to its locked position. 35 Means are also provided whereby, in an emergency, the gate or door or both can be released for opening without operation of the motor, as in case of failure of power, the car switch nevertheless remaining locked. There are also provided emergency devices, as sometimes required by statute or ordinance, whereby the car can be operated while the gate or door is open. Other features of the invention will be more particularly referred to hereinafter.

In the accompanying drawings, in which the invention is illustrated as embodied in an approved and practical form,

55 Figure 1 is a view in elevation, somewhat

diagrammatic, showing so much of an elevator car and its associated parts, together with a portion of a shaft door, as is necessary to enable the invention to be understood, some of the parts being, for clearness, shown slightly displaced from their preferred positions.

Figure 2 is a view in elevation of some of the parts shown in Figure 1, but on a larger scale, the parts above referred to as being shown displaced in Figure 1 being here shown in their proper relative positions.

Figure 3 is a composite sectional view on the plane indicated generally by the broken lines 3—3 of Figures 1 and 2, looking in the direction of the arrows, and on a larger scale than that of Figure 2.

Figure 4 is a detail view in section on the plane indicated by the broken line 4—4 of Figure 2, looking in the direction of the arrows, on a larger scale and with some parts added.

Figure 5 is a detail view in section on the plane indicated by the broken line 5—5 of Figure 2 looking in the direction of the arrows.

Figure 6 is a detail view in elevation showing the devices directly involved in the locking of the car switch.

Figure 7 is a view of the same partly in elevation and partly in section as seen from the right hand in Figure 6.

Figure 8 is a detail view in elevation showing particularly the devices for locking the shaft door.

Figure 9 is a detail view in elevation showing particularly the motor and its immediate connections.

Figure 10 is a group view showing successive positions of the valves which determine the movement of the motor piston.

Figure 11 is a view in elevation showing particularly the means for controlling the motor valves through the movement of the motor piston.

Figure 12 is a detail view of the valve controlling devices as seen from above.

Figures 13 and 14 are detail views showing also portions of the valve controlling devices.

Figures 15 and 16 are detailed views in elevation of the lever shown in Figure 1, in its two extreme positions of travel.

In the general assembly represented in Figure 1 of the drawings the car *a*, which

110

the fully closed position the valve h^2 remains in the same position as before and the valve h^3 is shifted to close the exhaust thereby cushioning the piston and its connections and preventing the slamming of the gate and door.

The connection of the carriage to each shaft gate is effected through a channeled shoe to be described which engages an arm c' of the shaft door. This arm has pivoted thereon a pawl c^2 which is adapted to engage a rack c^3 fixed on some part of the shaftway. This pawl has a cross head c^4 which is provided with pins c^5 and c^6 which lie in notches c^7 and c^8 in the edges of the arm c' . The first effect of movement of the shoe above mentioned with the carriage, is, through contact with the pin c^5 , to disengage the pawl c^2 from the rack c^3 so as to release the door, the continued movement of the shoe with the carriage through contact with the arm c' , effecting the movement of the door as above described. In the closing movement of the carriage the other side of the shoe contacts with the pin c^6 and holds the pawl away from the rack, thereby preventing noise.

The means whereby the valves h^2 and h^3 are controlled will now be described. To the stem h^4 of each valve h^2 and h^3 is secured a T-shaped fixture h^5 which has an arm h^6 and two arms h^7 and h^8 in different planes. Each arm h^6 carries a pin h^9 which is engaged by a slotted member i of a rod i' , the members i being slotted so as to permit movement of the valve stems independently of the movement of the rod i' while providing for movement of the valve stems through movement of the rod i' . The rod i' is connected through a bell crank i^2 and a rod i^3 with the operator's starting lever i^4 which is suitably mounted on the car. By suitable movement of the lever i^4 , the operator, therefore, is able to shift the valves h^2 and h^3 for the purpose of initiating the movement of the gate and door from either position of rest. The further shifting of the valves, during the movement of the gate and door, until they come to rest, is effected automatically. For this purpose there is connected to the piston rod f^8 , by arms k , a rod k' which partakes of the movement of the piston. This rod k' is armed with four lugs k^2 , k^3 , k^4 and k^5 , the lugs k^2 and k^3 co-operating respectively with the arms h^7 and h^8 of the valve h^2 and the lugs k^4 and k^5 co-operating respectively with the arms h^7 and h^8 of the valve h^3 . In the movement of the rod k' with the piston rod f^8 the lugs k^2 , k^3 , k^4 , k^5 , through the arms h^7 , h^8 of the two valves, effect the shifting of the valves illustrated in detail in Figure 10 and above described. As indicated in Figure 11 each of the lugs k^2 , k^3 , k^4 , k^5 , is secured adjustably on the rod k' as by a set screw k^6

so that the points of cut off and opening can be varied as the conditions of the particular installation may require.

It will be understood that after the initial operation of the valves by the operator, the arms h^6 , h^7 and h^8 of each valve stem h^4 are left at a position of about 45° to one side or the other of that shown in Figure 12, depending upon whether the carriage is started by the operator from the closed position or from the open position. In the movement of the rod k' above described the longer or higher lugs k^2 , k^4 , one of which, k^2 , is shown in Figure 14, will co-operate respectively with the arms h^7 in the higher plane and the shorter or lower lugs k^3 , k^5 , one of which is shown in Figure 13, will co-operate respectively with the arms h^8 in the lower plane.

The shoe above referred to, by which the reciprocating carriage is operatively engaged with each shaft door as required, indicated generally at l in Figures 1, 2 and 3, is movable toward and away from the plane of the arms c' of the several shaft doors, being moved into such plane for engagement with the arm as the elevator car is brought to rest in proper position with respect to the door to be opened, and being retired from such plane while the car is in motion so that neither through carelessness nor through accident will the shoe be in position to collide with any of the arms c' or other parts of the shaft during the movement of the car. To this end the shoe is connected to the carriage e by links l' , shown particularly in Figures 2 and 3 so that the shoe l may have a parallel movement with respect to the carriage. The shoe carries at its back a friction roller l^2 which bears against a bar m supported at the ends of the frame d by arms m' which are pivoted upon studs m^2 , shown particularly in Figure 2, so that the bar m can be moved toward or from the plane of the arms c' of the shaft doors. To effect such movement of the bar m it is provided on its rear side with a cam surface m^3 for co-operation with a roller m^4 which is carried by a vertically movable bracket m^5 , which has also a limited swinging movement in a plane parallel with the plane of the carriage. It is therefore guided at its lower end by a stem m^6 in a bracket m^7 which in turn is pivoted on a stud m^8 secured to one of the rails d' of the frame d . At its upper end the bracket m^5 is forked, as at m^9 to straddle a part n to be referred to, operative engagement of the bracket m^5 with such part n being effected through a pin m^{10} indicated in Figure 1 and by dotted lines in Figure 3.

The member n , above mentioned, slotted as at n' for engagement with the pin m^{10} , forms one arm of a three-armed lever n^2

which is pivoted at n^3 . One arm n^4 is notched as at n^5 for engagement with a pin n^6 on the carriage e .

When the carriage e is in the left hand position shown, the pin n^6 is in engagement with the notch n^5 of the lever n^2 . As the movement of the carriage to the right begins preparatory to the unlatching and opening of the door the pin n^6 carries the lever n^2 to the position indicated in Figure 15. This movement of the lever n^2 , through a slotted arm n , moves downward the bracket m^9 and the roller m^4 , co-acting with the cam surface m^3 of the bar m , moves the bar m to the right in Figure 3 and the bar m , co-acting with the roller l^2 , moves the shoe l from its normal position into position for engagement with the arm c' of the shaft door. As the carriage continues its movement the pin n^6 moves out of engagement with the notch n^5 , leaving the lever n^2 in the position shown in Figure 15. When the carriage returns to its left hand position, the door having been closed, the pin n^6 again enters the notch n^5 and moves the lever n^2 from the position shown in Figure 15 to the position shown in Figure 1, thereby, through the slotted arm n , raising the bracket m^9 and removing the roller m^4 from contact with the cam surface m^3 . The shoe l , by gravity, then swings back into its inoperative position.

The lever n^2 is also interconnected with the locking devices and in order that its relation thereto may be understood it will be necessary now to describe the interlocking devices.

The ordinary car switch, by which the movement of the car is controlled by the operator, is indicated at o . It is shown as having a segment o' which is notched as at o^2 for engagement with the locking rod o^3 . When the car is in motion the rod o^3 is down, out of the notch o^2 and the switch can then be operated to control the movement of the car. Whenever, however, the switch has been moved from its position of rest, the segment o' prevents upward movement of the locking rod o^3 and, through the devices to be described, prevents operation of the means to move the carriage. Likewise, when the starting switch is in the initial position and the movement of the valves to start the carriage is initiated, the locking rod is moved up into engagement with the last sector and in that position prevents the movement of the switch to start the car. In a convenient position, preferably below the floor of the car, the locking rod or an extension thereof passes through a housing o^4 , in which is mounted, on a stud o^5 , a cam o^6 which is adapted to co-operate with a roller bearing stud o^7 fixed in the locking rod. The cam o^6 is connected through an arm o^8 , a rod o^9 (see Figures 1, 6 and 7), which

has a lost motion connection o^{10} , a bell crank o^{11} and a rod o^{12} with the door controlling lever i^4 , so that when the lever i^4 is operated to initiate the shifting of the valves it brings about the opening of the door, the cam o^6 is operated to raise the locking rod o^3 and so lock the car switch against movement even before the actual movement of the door begins. The locking rod is engaged automatically and held in its raised or locking position by a counterweighted pawl or detent p , having a shoulder at p' for engagement with the other end of the stud o^7 , and in order that this pawl or detent may be disengaged and release the locking rod as soon as the gate operating carriage has been returned to its closed position, the pawl p is connected by a flexible connector p^2 with the arm n^4 of the three-armed lever n^2 above mentioned. As the carriage nears its closed position its pin n^6 , as above described, enters the notch n^5 in the arm n^4 of the lever and moves it from the position shown in Figure 15 to the position indicated in Figure 1, which movement, through the connector p^2 , withdraws the detent p and permits the locking rod to drop and to release the car switch o for further operation.

In the event of any failure of the motive power which is relied upon under ordinary conditions for the opening of the car gate or the shaft door it is desirable that it should be possible to open the door by the operator, a condition of safety being at the same time brought about by the interlocking of the car switch or controller and maintained thereafter as long as the door is open or unlocked. To this end there is provided a foot press or pedal q (in order that the operator's weight may be utilized), which is connected through a bell crank q' , with a link q^2 having a lost motion connection at q^3 , a bell crank q^4 , a link q^5 , a bell crank q^6 , and a slotted rod q^7 with the arm n^7 of the three-armed lever n^2 above mentioned. Pressure on the foot press q pulls the lever n^2 from the position indicated in Figure 1 toward the position shown in Figure 15. It is a characteristic of the devices disclosed herein that complete closing of the door takes place a little before the carriage e completes its movement. The shoe l , therefore, is carried, in the closing movement, a little beyond the position of the arms c' . Consequently the first effect of the above described movements of the lever n^2 , through the notch n^5 and pin n^6 , is to move the carriage until the shoe is in approximate alignment, horizontally, with the arms c' . The slot n' in the arm n permits this time relation of the movement of the carriage with respect to the movement of the shoe l into engagement with the arms c' which is brought about by the engagement of the upper end of the slot n' with the pin m^{10} of the

bracket m^5 , the downward movement of the bracket m^5 and the forward movement of the bar m to advance the shoe l into engagement with the arms c' . The movement 5 of the bell crank q' , through a link q^8 , effects movement of the cam o^6 to raise the locking rod o^3 and thereby prevent movement of the car switch. The provision of the lost motion devices at o^{10} and q^3 permits 10 operation of either the foot press q or the door controlling lever i^4 independently of the other.

It has just been stated that the carriage, in its closing movement, moves a little after 15 the shaft door has been completely closed. Such movement is ordinarily effected by the motive power supply, but when such power fails, as has just now been assumed, it is 20 obvious that some other means must be provided to continue the movement of the carriage for a little after the door has been closed completely by the operator. For this purpose a spring n^8 is connected to the arm n^4 in which energy is stored during the 25 movement of the lever n^2 from the position indicated in Figure 1 to the position shown in Figure 15. The lever n^2 is held in its secondary position as well in operation under normal conditions as in operation under 30 the abnormal condition last referred to, that is, in the event of failure of power, by a spring pressed detent n^9 which normally holds the lever n^2 in its secondary position and is acted upon by the door, in the last of 35 its closing movement, to release the lever n^2 so that, through the energy stored in the spring n^8 , the movement of the carriage will be continued for a little after the door has been closed completely. Of course the spring 40 n^8 acts even when the mechanism is operated under normal conditions but under normal conditions the motor is the main factor in the return of the carriage to its extreme left hand position.

45 It will be understood that in practice the car gate b will be disengaged from the carriage e through operation of the latch b' and the gate opened in order that the operator may have access to the shaft door c for the purpose of opening it. It will also be understood that through disengagement 50 of the clutch member g^3 it is possible to disconnect the carriage from the motor and therefore obviate the necessity of moving the motor piston when the shaft door is to be opened by hand as above described.

55 Statutes or ordinances sometimes require that in elevator installations it shall be possible to move the car even when the car gate or the shaft doors are opened. To meet this requirement the detent n^9 which holds the lever n^2 in its secondary position, is connected by a flexible connector n^{10} with an emergency pull indicated at n^{11} . When the lever 60 n^2 has been moved into its secondary posi-

tion the operation of the car switch, to move the car, is prevented under ordinary conditions, but the release of the detent n^9 by the emergency means just described permits the lever n^2 to return to its normal or initial position, notwithstanding the fact that the opening movement of the gate or door has commenced, and therefore unlocks the car switch and permits the car to be moved.

65 The operation of the several parts of the improved structure has been explained in connection with the description of the construction of such parts. The operation in general may be briefly described as follows:

Motive power being supplied from any suitable source and the parts being in the positions represented in Figure 1 (with some displacement for the sake of clearness) and in Figures 2 and 3, with the carriage in its extreme left hand position, the car gate fully 70 closed, the car in position at a landing and at rest, and the shaft door fully closed, the operator pulls down the handle of the lever i^4 . This movement shifts the cam o^6 to raise the locking rod o^3 into engagement with the 75 car switch and prevent operation thereof to start the car either up or down. The same movement shifts the valves h^2 and h^3 from the positions shown in part I of Figure 10 to the position shown in part II thereof and 80 this operation starts the movement of the carriage to the right and then moves the shoe l into engagement with the arm c' . Through the connection of the shaft door in this manner and of the car gate through 85 the arm e' with the carriage both the gate and the door are moved together toward the right. As the carriage moves toward its right hand position, first the air is cut off from the driving end of the cylinder and then the exhaust at the other end is closed 90 so that the carriage is cushioned and the door and gate open together without slamming. When the door and gate are to be 95 closed the handle of the lever i^4 is moved up and the valves h^2 and h^3 are shifted so as to bring about the movement of the carriage in the opposite direction, such movement being 100 continued and finally cushioned substantially as above described. The operation under 105 abnormal conditions has already been described sufficiently and no further explanation is necessary.

110 It will be understood that various changes in details of construction and arrangement 115 can be made to suit different conditions of use and that some of the parts or features of the mechanism described can be omitted or replaced by others without affecting the operation of the remaining parts. The invention, therefore, except as pointed out in the claims, is not limited to the particular construction and arrangement and combination of parts shown and described herein.

120 I claim as my invention:

1. In an elevator, the combination of a car, a car gate, a reciprocating carriage and a readily manually detachable connection between the car gate and the reciprocating carriage.
2. In an elevator, the combination of a car, a car gate, a reciprocating carriage and a spring pressed latch mounted on the car gate and forming a readily detachable connection between the same and the carriage.
3. In an elevator, the combination of a car, a reciprocating carriage mounted on the car, a vertically channeled shoe supported on the carriage, a shaft door having an arm to be engaged by the shoe, a fixed rack, and a T-headed pawl adapted to engage said rack and pivoted on said arm and having a pin disposed at the side of said arm and adapted to be engaged by the side of the channeled shoe to disengage the pawl from said rack preliminary to and during the movement of the arm with the shoe.
4. In an elevator, the combination of a car, a frame mounted on the car, a reciprocating carriage mounted on the frame, an air cylinder, piston and piston rod mounted on the car, a driving pulley and idler mounted on the frame, a cable having its ends connected to the piston rod and passed about the driving pulley and the idler, a second driving pulley also mounted on the frame in operative relation with the first mentioned pulley, a corresponding idler, and a cable passed around the second driving pulley and idler and having its ends connected to the reciprocating carriage.
5. In an elevator, the combination of a car, a frame mounted on the car, a reciprocating carriage mounted on the frame, an air cylinder, piston and piston rod mounted on the car, a driving pulley and idler mounted on the frame, a cable having its ends connected to the piston rod and passed about the driving pulley and the idler, a second driving pulley also mounted on the frame in operative relation with the first mentioned pulley, a corresponding idler, a cable passed around the second driving pulley and idler and having its ends connected to the reciprocating carriage, and a manually controlled clutch between the driving pulleys.
6. In an elevator, the combination of a car, a reciprocating carriage, a shaft door, a shoe movably mounted on the carriage, and means to move the shoe bodily toward and from the shaft door and into and out of operative engagement therewith.
7. In an elevator, the combination of a car, a reciprocating carriage, a shaft door, a shoe mounted movably on the carriage and adapted for operative engagement with the shaft door, a bar mounted on the carriage in operative relation with the shoe and movable to effect operative engagement of the shoe with the shaft door, said bar having a cam surface, a vertically movable bracket for co-operation with said cam surface, and means to move the bracket in a vertical direction to effect movement of the shoe into operative engagement with the shaft door.
8. In an elevator, the combination of a car, a reciprocating carriage, a shaft door, a shoe mounted movably on the carriage and adapted for operative engagement with the shaft door, parallel links supporting the shoe from the carriage, a bar mounted on the carriage in operative relation with the shoe and movable to effect operative engagement of the shoe with the shaft door, said bar having a cam surface, a vertically movable bracket for co-operation with said cam surface, and means to move the bracket in a vertical direction to effect movement of the shoe into operative engagement with the shaft door.
9. In an elevator, the combination of a car, a reciprocating carriage, a shaft door, a shoe mounted movably on the carriage and adapted for operative engagement with the shaft door, depending parallel links supporting the shoe from the carriage, a bar mounted to swing on the carriage in operative relation with the shoe and movable to effect operative engagement of the shoe with the shaft door, said bar having a cam surface, a vertically movable bracket for co-operation with said cam surface, and means to move the bracket in a vertical direction to effect movement of the shoe into operative engagement with the shaft door.
10. In an elevator, the combination of a car, a reciprocating carriage, a shaft door, a shoe mounted movably on the carriage and adapted for operative engagement with the shaft door, a bar mounted on the carriage in operative relation with the shoe and movable to effect operative engagement of the shoe with the shaft door, said bar having a cam surface, a vertically movable bracket for co-operation with said cam surface, a lever mounted on the car and adapted for operative engagement with the carriage, and intermediate connections whereby, on movement of the lever with the carriage, the bracket is moved to actuate the bar and to move the shoe into operative engagement with the shaft door.
11. In an elevator, the combination of a car, a reciprocating carriage, a shaft door, a shoe mounted movably on the carriage and adapted for operative engagement with the shaft door, a bar mounted on the carriage in operative relation with the shoe and movable to effect operative engagement of the shoe with the shaft door, said bar having a cam surface, a vertically movable bracket for co-operation with said cam surface, a lever mounted on the car and adapted for operative engagement with the carriage, and an

arm connected with said lever and slotted for engagement with the vertically movable bracket.

12. In an elevator, the combination of a car, a reciprocating carriage, a shaft door, a shoe mounted movably on the carriage and adapted for operative engagement with the shaft door, a bar mounted on the carriage in operative relation with the shoe and movable to effect operative engagement of the shoe with the shaft door, said bar having a cam surface, a vertically movable bracket for co-operation with said cam surface, a lever mounted on the car and adapted for operative engagement with the carriage, an arm connected with said lever and slotted for engagement with the vertically movable bracket, and a pivoted support for said bracket to permit limited swinging movement of the bracket with said lever and arm.

13. In an elevator, the combination of a car, a reciprocating carriage mounted on the car, a shoe mounted movably on the car for movement into and out of operative engagement with a shaft door, a lever mounted on the car and adapted for operative engagement with the carriage, and intermediate means actuated by movement of the lever to effect movement of the shoe into operative engagement with the shaft door.

14. In an elevator, the combination of a car, a reciprocating carriage mounted on the car, a shoe mounted movably on the car for movement into and out of operative engagement with a shaft door, a lever mounted on the car and adapted for operative engagement with the carriage, intermediate means actuated by movement of the lever to effect movement of the shoe into operative engagement with the shaft door, and a spring in which energy is stored by the movement of the lever in the opening movement of the carriage and by which energy is returned to the lever to complete the closing movement of the carriage.

15. In an elevator, the combination of a car, a reciprocating carriage mounted on the car, a shoe mounted movably on the car for movement into and out of operative engagement with a shaft door, a lever mounted on the car and adapted for operative engagement with the carriage, intermediate means actuated by movement of the lever to effect movement of the shoe into operative engagement with the shaft door, and a detent for engagement with the lever to prevent movement thereof from its secondary position after movement with the carriage in the opening movement of the carriage, said detent being also in operative relation with the carriage to release the lever during the last of the closing movement of the carriage.

16. In an elevator, the combination of a car, a reciprocating carriage mounted on the car, a shoe mounted movably on the car

for movement into and out of operative engagement with a shaft door, a lever mounted on the car and adapted for operative engagement with the carriage, intermediate means actuated by movement of the lever to effect movement of the shoe into operative engagement with the shaft door, a detent for engagement with the lever to prevent movement thereof from its secondary position after movement with the carriage in the opening movement of the carriage, said detent being also in operative relation with the carriage to release the lever during the last of the closing movement of the carriage, and means under control of the operator for actuating the detent to release the lever.

17. In an elevator, the combination of a car, a reciprocating carriage mounted on the car, a shoe mounted movably on the car for movement into and out of operative engagement with a shaft door, a lever mounted on the car and adapted for operative engagement with the carriage, intermediate means actuated by movement of the lever to effect movement of the shoe into operative engagement with the shaft door, a detent for engagement with the lever to prevent movement thereof from its secondary position after movement with the carriage in the opening movement of the carriage, said detent being also in operative relation with the carriage to release the lever during the last of the closing movement of the carriage, and means under the control of the operator to move the lever to initiate the opening movement of the carriage.

18. In an elevator, the combination of a car, a reciprocating carriage mounted on the car, a shoe mounted movably on the car for movement into and out of operative engagement with a shaft door, a lever mounted on the car and adapted for operative engagement with the carriage, intermediate means actuated by movement of the lever to effect movement of the shoe into operative engagement with the shaft door, a detent for engagement with the lever to prevent movement thereof from its secondary position after movement with the carriage in the opening movement of the carriage, said detent being also in operative relation with the carriage to release the lever during the last of the closing movement of the carriage, power driven means to reciprocate the carriage, and means under the control of the operator to move the lever to initiate the opening movement of the carriage.

19. In an elevator, the combination of a car, a reciprocating carriage mounted on the car, a shoe mounted movably on the car for movement into and out of operative engagement with a shaft door, a lever mounted on the car and adapted for operative engagement with the carriage, intermediate means actuated by movement of the lever to effect

locking rod in locking position, and means to move the detent to release the locking rod.

26. In an elevator, the combination of a car, a controlling device, a locking rod therefor, a cam to move the locking rod to locking position, means to actuate the cam, a counterweighted pivoted detent to retain the locking rod in locking position, and means to move the detent against the counterweight to release the locking rod.

27. In an elevator, the combination of a car, door operating means mounted on the car, a fluid pressure motor for said operating means the same comprising a cylinder, a piston and a piston rod, valves to control the admission and exhaust of the motive fluid to and from the cylinder, said valves

having valve stems, arms connected to the valve stems, means under the control of the operator and connected to said arms whereby the valves are shifted to initiate the movement of the piston, other arms also connected to the valve stems, a rod connected to the piston rod to move therewith, and lugs mounted on said rod for co-operation with said other arms of the valve stems, whereby the admission and exhaust of motive fluid to the cylinder is controlled by movement of the piston rod after initiation of its movement under control of the operator.

This specification signed this 9th day of August, A. D. 1923.

LOUIS CHASAN.
